UNITED STATES PATENT OFFICE.

CHARLES F. ROPER, OF HOPEDALE, MASSACHUSETTS, ASSIGNOR TO DRAPER COMPANY, OF HOPEDALE, MASSACHUSETTS, A CORPORATION OF MAINE.

TAKE-UP CONTROL FOR LOOMS.

SPECIFICATION forming part of Letters Patent No. 729,668, dated June 2, 1903.

Application filed February 2, 1903. Serial No. 141,510. (No model.)

To all whom it may concern:

Be it known that I, CHARLES F. ROPER, a citizen of the United States, and a resident of Hopedale, county of Worcester, State of Massachusetts, have invented an Improvement in Take-Up Control for Looms, of which the following description, in connection with the accompanying drawings, is a specification, like characters on the drawings representing like parts.

This invention has for its object the production of means for so controlling the take-up mechanism of a loom that take-up will be arrested under certain conditions, particularly when the protector mechanism operates.

In looms provided with "antibang" mechanism the crank-shaft may turn over a number of times after the protector mechanism operates without causing any damage as the warps are slackened, so that the shuttle cannot break them even if it stops in the shed. As the shuttle is not picked during such movement of the loom, the take-up should not act. Now if the shuttle stops within the shed, but not in front of the filling fork or detector, the absence of filling is detected by the fork, and such detecting action arrests or prevents take-up. On the other hand, if the shuttle stops in front of the fork it will tilt the latter, and thereby prevent the arrest of take-up by the filling-detecting means.

My present invention obviates this difficulty by providing for the arrest of take-up by or through the operation of the protector mechanism, and this is effected in a very simple and efficient manner. So long as there is no shuttle fault the take-up mechanism will be controlled by the filling-detecting means, as is the case in my United States Patent No. 716,282, dated December 16, 1902; but upon the occurrence of a shuttle fault the protector assumes joint control of the take-up.

The various novel features of my invention will be described in the subjoined specification and particularly pointed out in the following claims.

Figure 1 is a view, partly in transverse section and partly in right-hand side elevation, of a loom having one embodiment of my in-

vention applied thereto, the loom being provided with antibang mechanism. Fig. 2 is a front elevation of the main portion of the take-up mechanism located at the shipper side of the loom. Fig. 3 is an enlarged side elevation of the take-up ratchet and its actuating-pawl. Fig. 4 is a face view of the pawl and ratchet placed side by side and showing their co-operating faces. Fig. 5 is a sectional view on the line 5-6, Fig. 2, looking toward the left, showing the manner in which take-up is arrested by or through the filling-detecting means. Fig. 6 is a similar view, but showing the arrest of take-up by or through the action of the protector mechanism; and Fig. 7 is an enlarged detail of a portion of the mechanism shown in Figs. 5 and 6, by which the take-up is arrested.

The breast-beam 2, lay 3, lay-sword 4, the controlling or operating rock-shaft 6, having an upturned arm 7 in the path of the slide f^3 of the filling fork or detector f^x , Fig. 1, of any usual construction, the take-up roll 11, its shaft 12, having an attached worm-gear 15 in mesh with a worm 16, fast on a shaft 17, the bracket 14, in which said shaft is rotatably mounted, and the ratchet 21, fast on the shaft and having circularly-arranged teeth 22 on its inner face, may be and are all as in my Patent No. 716,282.

The actuating-pawl 27, pivotally mounted on shaft 17 and provided with an elongated opening 28, (see Fig. 4,) its tooth or lug 29 to co-operate with the ratchet, the projections 30 to bear on the inner face of the ratchet, the guide-arm 31, and the depending finger 32 are also substantially as in said patent, the arm 31 being connected by a link 35 with the arm 37, attached to the lay-sword, the vibrations of the lay operating the pawl.

A spring 33 yieldingly maintains the pawl in co-operative engagement with the ratchet when the loom is running properly.

In my patent the controlling rock-shaft 6 has a bent and downturned arm 41, which extends in front of the pawl-finger 32, so that when the rock-shaft is turned by or through an abnormal condition of the filling, such as failure or breakage or its substantial ex-

haustion in the shuttle, said arm 41 acts to tip the pawl and prevent the engagement of the pawl-lug 29 with the ratchet-teeth, thereby arresting the take-up.

5 In my present invention the rock-shaft 6 is also provided with a downturned arm, as 41; but it does not engage the pawl, though it is arranged to arrest take-up upon the occurrence of an abnormal condition of the filling. Herein the free end of the arm 41 has pivotally connected with it a longitudinally-movable bar 42, extended toward the back of the loom, and at its rear end said bar is reduced in size, as at 43, to rest upon the upper edge 52 of an ear 51, extended laterally from a bracket 50, secured to the loom side. Adjacent the part 43 of the bar the latter is provided with upper and lower cam-faces 44 and 45, (see Fig. 7,) oppositely inclined or beveled, the lower face 45 being adapted to engage and ride up on the face 53 of the ear 51 when the bar is moved rearwardly in the direction of arrow 100. The bracket 50 has fulcrumed upon it at 54 a rocking or tilting member 61 62, the part 61 being upturned for a purpose to be described, while the depending part 62 is segmental in shape and is provided with an inclined lateral shelf 63 in the path of the cam-face 44. A link 46 is pivotally connected at 47 with the back of the pawl-finger 32, and the other end of the link is pivotally connected at 48 with the segmental part 62 of the rocking or tilting member. The normal position of the parts is shown in Figs. 1 and 7 when the loom is working properly. If the rock-shaft 6 is turned by the outward swing of arm 7, however, the depending arm 41 is swung backward, moving the bar 42 in the direction of arrow 100, Fig. 7, and the cam-face 45 rides up on the face 53 of the ear 51, lifting the rear end of the bar. The cam-face 44 also engages the shelf 63, and as said cam-face is moved rearwardly and also upward the engagement with the shelf operates to turn the member 61 62 on its fulcrum in the direction of arrow 99, Fig. 7, and through the link 46 the pawl is tipped into the position shown in Fig. 5, disengaging the pawl-lug 29 from the ratchet-teeth and arresting take-up. When the rock-shaft 6 returns to its normal position, the bar 42 is withdrawn to its normal position, the part 43 thereof dropping down upon the ear 51, and the pawl is moved into co-operative engagement with the ratchet by the spring 33.

In order to provide for control of the take-up at times by the protector mechanism, I have provided means whereby the member 61 62 will be rocked or tilted upon the operation 60 of the protector mechanism. A live frog *c* is mounted on the loom side to be engaged and moved by the dagger *d*³ of the protector mechanism, Fig. 1, upon improper boxing of the shuttle, said frog acting, through a knock-off lever *c*² *c*³, Fig. 2, to release the shipper *L*. The whip-roll *W*, Fig. 1, is mounted in arms *m*', fulcrumed at *m*, and maintained locked

in position under normal circumstances by means forming no part of this invention, one member of such means being shown at *n*², 70 however. The locking means is controlled by means of a link *n*¹², connecting the frog with an upturned arm *n*¹⁰, fast on a rock-shaft *N*, to which the member *n*² is secured, substantially as in an application, Serial No. 75 134,234, filed by me January 9, 1903. When the frog is engaged and moved forward by the dagger upon improper boxing of the shuttle, the link *n*¹² is moved by the frog to swing the arm *n*¹⁰ forward, unlocking the whip-roll 80 and causing the same to move to slacken the warps, the same forward movement of the frog releasing the shipper. This is an anti-bang mechanism, the loom being free to turn over one or more times after shipper release, 85 the positive slackening of the warps preventing any breakage of the same if the shuttle stops in the shed. The upturned part 61 of the rocking or tilting member 61 62 is located in front of the frog, and when the latter is 90 moved forward, as described, it engages the part 61 and depresses it, as shown in Fig. 6, swinging the member on its fulcrum 54 in the direction of the arrow 99, Fig. 7. Thereby the link 46 is moved longitudinally to tilt the 95 pawl on the shaft 17, disengaging the lug 29 from the ratchet-teeth and arresting take-up by or through the operation of the protector mechanism. It will be manifest, therefore, that the rocking or tilting member 61 62 and 100 its connection with the pawl will be operated to arrest take-up by or through some abnormal condition of the filling or by or through the operation of the protector mechanism.

The stoppage of the shuttle in the shed in 105 front of the filling-fork and acting to tilt the latter, as has been before referred to, would manifestly prevent arrest of take-up at such time were the control of the take-up wholly dependent upon the filling-fork.

By causing the operation of the protector mechanism to arrest take-up, however, the failure of the fork to secure the desired effect is corrected and arrest of take-up insured at 110 the proper time.

My invention is not restricted to the precise construction and arrangement herein shown and described, as the same may be varied or changed in different particulars without departing from the spirit and scope of my invention, only one practical embodiment thereof being referred to herein.

Having fully described my invention, what I claim as new, and desire to secure by Letters Patent, is—

1. In a loom, take-up mechanism, a filling-detector, protector mechanism, including a frog, and means operated by or through detection of filling failure and also by actuation of the frog to arrest take-up.

2. In a loom, take-up mechanism, including a ratchet and actuating-pawl, a filling-detector, protector mechanism, a rocker, and a link connecting it with the pawl, operation

- of the protector mechanism or detecting action of the filling-detector causing the rocker to turn and disengage the pawl from the ratchet, to arrest take-up.
5. In a loom, take-up mechanism, including a ratchet and actuating-pawl, a rocking releasing device connected with the latter, protector mechanism, a filling-detector, and separate operating connections between them and the releasing device, to rock the latter and release the pawl from coöperation with the ratchet upon filling failure or the operation of the protector mechanism.
10. In a loom, take-up mechanism, protector mechanism, including a frog, and means actuated by movement of the frog to arrest take-up when the protector mechanism operates.
15. In a loom, take-up mechanism, protector mechanism, including a dagger on the lay and a live frog with which it coöperates at times, and means actuated by movement of the frog upon engagement with the dagger to arrest take-up.
20. In a loom, take-up mechanism, including a ratchet and actuating-pawl, a rocker, a link operatively connecting it with the pawl, a filling-fork, its slide, connections between the latter and the rocker to turn the latter when the slide is moved, to thereby disengage the pawl and ratchet and arrest take-up, and protector mechanism, including a frog movable into engagement with and to operatively turn the rocker when the protector mechanism operates.
25. In a loom, a lay, protector mechanism, including a dagger carried by the lay and a live frog to be moved by engagement with the dagger, take-up mechanism, including a ratchet and actuating-pawl, and means, including a tilting member in the path of the frog, to disengage the pawl and ratchet when the frog is moved by coöperation with the dagger.
30. In a loom, a lay, a shuttle, a filling-de-
- tector, protector mechanism, including a live frog, whereby the loom may turn over when said mechanism operates, take-up mechanism, and means controlled by either the filling-detector or the frog according to the position of the shuttle in the shed to arrest take-up when the protector mechanism is called into operation.
35. In a loom, take-up mechanism, a whip-roll, protector mechanism, including a live frog, means operated by movement of the latter to positively move the whip-roll and slacken the warps, and means actuated by such movement of the frog to arrest take-up.
40. In a loom, take-up mechanism, protector mechanism, including a live frog, means to positively slacken the warps when the frog is moved by operation of the protector mechanism, and means actuated directly by such movement of the frog to arrest take-up.
45. In a loom, take-up mechanism, a filling-detector, protector mechanism, including a frog, means governed by the latter to positively slacken the warps upon operation of the protector mechanism, and means actuated directly by said frog and indirectly by detecting action of the filling-detector, to arrest take-up.
50. In a loom, take-up mechanism, a whip-roll, protector mechanism, including a live frog, means operated by movement of the latter to positively move the whip-roll and slacken the warps, and means actuated by such movement of the frog to arrest take-up.
55. In a loom, take-up mechanism, protector mechanism, including a live frog, means to positively slacken the warps when the frog is moved by operation of the protector mechanism, and means actuated directly by such movement of the frog to arrest take-up.
60. In a loom, take-up mechanism, a filling-detector, protector mechanism, including a frog, means governed by the latter to positively slacken the warps upon operation of the protector mechanism, and means actuated directly by said frog and indirectly by detecting action of the filling-detector, to arrest take-up.
65. In a loom, take-up mechanism, a filling-detector, protector mechanism, including a frog, means governed by the latter to positively slacken the warps upon operation of the protector mechanism, and means actuated directly by said frog and indirectly by detecting action of the filling-detector, to arrest take-up.
70. In a loom, a warp-tension-controlling instrumentality, positively-acting means operated by or through improper boxing of the shuttle to cause said instrumentality to slacken the warps, take-up mechanism, and a device to effect arrest of take-up by or through the actuation of said positively-acting means.
75. In testimony whereof I have signed my name to this specification in the presence of subscribing witnesses.
